US0D1074665S

(12) **United States Design Patent** (10) **Patent No.:** **US D1,074,665 S**
(45) **Date of Patent:** **** May 13, 2025**

(54) **ELECTRONIC DEVICE**

(71) Applicant: **Apple Inc.**, Cupertino, CA (US)

(72) Inventors: **Jody Akana**, San Francisco, CA (US); **Bartley K. Andre**, Palo Alto, CA (US); **Jeremy Bataillou**, San Francisco, CA (US); **Daniel J. Coster**, San Francisco, CA (US); **Daniele De Iuliis**, San Francisco, CA (US); **M. Evans Hankey**, San Francisco, CA (US); **Julian Hoenig**, San Francisco, CA (US); **Richard P. Howarth**, San Francisco, CA (US); **Jonathan P. Ive**, San Francisco, CA (US); **Duncan Robert Kerr**, San Francisco, CA (US); **Shin Nishibori**, Kailua, HI (US); **Matthew Dean Rohrbach**, San Francisco, CA (US); **Peter Russell-Clarke**, San Francisco, CA (US); **Christopher J. Stringer**, Woodside, CA (US); **Eugene Antony Whang**, San Francisco, CA (US); **Rico Zörkendorfer**, San Francisco, CA (US)

(73) Assignee: **Apple Inc.**, Cupertino, CA (US)

(**) Term: **15 Years**

(21) Appl. No.: **29/814,098**

(22) Filed: **Nov. 3, 2021**

Related U.S. Application Data

(60) Continuation of application No. 29/660,118, filed on Aug. 17, 2018, now Pat. No. Des. 936,647, which is a continuation of application No. 29/605,839, filed on May 31, 2017, now Pat. No. Des. 829,711, which is a continuation of application No. 29/554,646, filed on Feb. 12, 2016, now Pat. No. Des. 791,763, which is a division of application No. 29/497,123, filed on Jul. 21, 2014, now Pat. No. Des. 752,035, which is a division of application No. 29/431,443, filed on Sep. 7, 2012, now Pat. No. Des. 712,397.

(57) CLAIM

The ornamental design for an electronic device as shown and described.

DESCRIPTION

FIG. 1 is a perspective view of an electronic device showing our new design;

FIG. 2 is a rear perspective view thereof;

FIG. 3 is another rear perspective view thereof;

FIG. 4 is a front view thereof;

FIG. 5 is a rear view thereof;

FIG. 6 is a left side view thereof;

FIG. 7 is a right side view thereof;

FIG. 8 is a top view thereof;

FIG. 9 is a bottom view thereof;

FIG. 10 is a perspective view of a second embodiment thereof;

FIG. 11 is a rear perspective view thereof;

FIG. 12 is another rear perspective view thereof;

FIG. 13 is a front view thereof;

FIG. 14 is a rear view thereof;

FIG. 15 is a left side view thereof;

FIG. 16 is a right side view thereof;

FIG. 17 is a top view thereof; and,

FIG. 18 is a bottom view thereof.

The broken lines illustrate portions of the article which form no part of the claimed design.

The relatively light shade lines on the surface portions indicate contour and not surface decoration.
